CROCK HANDLE

Filed Nov. 25, 1929

Fig. I.

Fig. 2.

Fig. 3

A technical drawing of a cylindrical component. It features a central vertical slot and a horizontal slot intersecting it. The top edge has three labels: '3.' on the left, '9' in the center, and '11' on the right. The bottom edge has three labels: '4' on the left, '12' on the right, and '1' at the bottom center.

UNITED STATES PATENT OFFICE

COMMODORE B. WOODMAN, OF OAKLAND, CALIFORNIA, ASSIGNOR OF ONE-THIRD TO OSCAR HOFFMAN AND ONE-THIRD TO ARTHUR J. FLEUTI, BOTH OF SAN FRANCISCO, CALIFORNIA

CROCK HANDLE

Application filed November 25, 1929. Serial No. 409,667.

My invention relates to improvements in handles for earthen crocks, jars, and the like, wherein a ring formed from adjustably connected ring segments is arranged to be adjustably fitted around the top of a crock and clamped into engagement with said crock, said ring being provided with handles disposed upon opposite sides of the crock whereby the crock may be lifted.

10 The primary object of my invention is to provide an improved handle adapted to be mounted upon earthen crocks and the like to facilitate the lifting thereof.

Another object is to provide an improved 15 crock handle which may be readily adjusted and secured upon crocks of various size.

A further object is to provide an improved 20 crock handle which may be quickly and easily attached and detached from a crock to facilitate the transfer of the handle from one crock to another.

Another object is to provide an improved 25 clamping means whereby the handle may be easily and effectually clamped onto the top of a crock.

A still further object is to provide an improved device of the character described which is simple and efficient in operation, and of rugged and economical construction.

30 I accomplish these and other objects by means of the improved device disclosed in the drawings forming a part of the present application wherein like characters of reference are used to designate similar parts throughout the drawings and specifications, and in which—

Fig. 1 is a plan view of my improved crock handle, and indicating the manner in which the mounting ring may be adjusted to various 35 sizes;

Fig. 2 is a side elevation of the handle as fitted upon a crock, and showing the clamping means;

Fig. 3 is a sectional detail taken upon the 40 line 3—3 of Fig. 2 in the direction indicated; and

Fig. 4 is a sectional detail taken upon the line 4—4 of Fig. 1 in the direction indicated.

Referring to the drawings, the numerals 45 50 1 and 2 are used to designate in general a

pair of arcuate ring segments formed from heavy wire or other suitable material shaped to substantially semi-circular form, and each provided with outwardly turned end portions 55 3 and 4. The segments 1 and 2 are each provided with outwardly disposed indentations 6 spaced substantially equally from the ends of the segments. Suitable handles 7 are mounted upon the segments 1 and 2, preferably by means of eyelets 8 engaging the 60 indentations 6, as indicated in the drawings.

Connecting bands 9 engage and adjustably connect adjacent ends of the segments 1 and 2. The bands 9 comprise flat strips of suitable material having inwardly turned ends 11 65 apertured as at 12 to receive and form bearings from the ends of the segments 1 and 2. A plurality of apertures 14 are spaced longitudinally along the bands 9, and one of the bands is also provided with a longitudinally 70 disposed slot 16.

The segment 1 is slidably movable through the adjacent bearing portions 11 of the bands 9 into overlapping relation with the bands, the ends 3 and 4 being movable into engagement with any desired apertures 14 for adjusting the size of the ring to a desired diameter. The opposite segment 2 has one end extending through the adjacent bearing portion 11 and the outwardly turned end 3 is 80 moved into engagement with an aperture 17 adjacent to said portion 11, said end preferably being riveted to permanently secure the segment 2 to said band. The opposite end of the segment 2 is slidably movable through 85 the adjacent band portion 11 and has its outwardly turned end 4 extending outwardly through the slot 16.

A clamping lever 18 is pivotally mounted upon the band 9 adjacent the slot 16. A 90 toggle link 19 is pivotally connected at one end to the lever 18 and at its opposite end to the outwardly extending end 4 of the segment 2. The lever 18 is provided with an inwardly turned end 21, notched as at 22 to engage the 95 segment 2 to normally hold the lever in its clamping position, said lever being adapted to be sprung outwardly to disengage the segment when desired.

In operation, the ring is adjusted to extend 100

around the top of an earthen crock 23, or the like, having the usual bead 24 forming a rim around the top of the crock. To adjust the ring, the ends 3 and 4 of the segment 1 are sprung inwardly to disengage the apertures 14 of the bands 9, and the segment is moved to overlap the bands 9 sufficiently to adjust the diameter of the ring to approximately fit the top of the jar, the clamping lever 18 being first swung to its releasing position as shown in full lines in Fig. 2 of the drawings. When the ring has been thus substantially fitted to the top of the crock, the ends 3 and 4 of the segment 1 are pressed into engagement with the nearest apertures 14. The lever 18 is then swung to its clamping position as shown in dotted lines in Fig. 2, thereby moving the toggle link 19 into alinement with the lever 18 and forcing the end 4 of the segment 2 along the slot 16, thereby contracting the segment 2 into clamping engagement with the top of the crock. As the lever 18 is moved to its clamping position, it is sprung outwardly sufficiently to permit the notch 22 to engage the segment and thereby normally retain the lever in its clamping position.

The handle members 7 mounted upon the indentations 6 normally hang suspended at the sides of the crock 23 at diametrically opposed points, said members being pivotally movable to extend upwardly above the top of the crock, as shown in Fig. 2 whereby the handles may be conveniently gripped for lifting the crock. The indentations permit free movement of the eyelets 8 upon the segments 1 and 2, said indentations operating to hold the eyelets 8 in spaced relation to the walls of the crock when the segments are clamped around the top of the crock.

40 The specific details of construction and arrangement may be modified in various ways without departing from the spirit of my invention. I therefore do not wish to be restricted to the precise details illustrated and described, but desire to avail myself of all modifications which may fall within the scope of the appended claims.

Having thus described my invention what I claim as new and desire to secure by Letters 50 Patent is—

1. A crock handle comprising a ring formed from a pair of ring segments each provided with outwardly turned ends; a pair of connecting bands apertured to adjustably engage and connect adjacent ends of the segments to vary the diameter of the ring to fit around the top of a crock, one of said bands having a longitudinally disposed slot engaging an end of a segment; a clamping lever 55 pivotally mounted upon said band adjacent the slot; a toggle link pivotally connected to the lever and to the adjacent end of the segment for moving said segment into clamping engagement with the top of the crock; 60 and a pair of handle members mounted upon

the segments and disposed upon opposite sides of the crock whereby the crock may be lifted.

2. A crock handle comprising a ring formed from a pair of ring segments each provided with outwardly turned ends; a pair of connecting bands apertured to adjustably engage and connect adjacent ends of the segments to vary the diameter of the ring to fit around the top of a crock, one of said bands having a longitudinally disposed slot engaging an end of a segment; a clamping lever pivotally mounted upon said band adjacent the slot; a toggle link pivotally connected to the lever and to the adjacent end of the segment for moving said segment into clamping engagement with the top of the crock; a pair of handle members mounted upon the segments and disposed upon opposite sides of the crock whereby the crock may be lifted; and means formed upon the end of the lever and movable into engaging relation to the adjacent segment to normally hold said lever in clamping position.

In witness whereof, I hereunto set my signature.

COMMODORE B. WOODMAN.
